UNITED STATES PATENT OFFICE.

CHARLES FORBES, OF GRAND RAPIDS, MICHIGAN.

MEANS FOR COOLING INTERNAL-COMBUSTION ENGINES.

Application filed March 18, 1927. Serial No. 176,311.

The present invention relates to means for cooling internal-combustion engines; and its object is to provide means of that character which shall be simple and economical in construction; and, more particularly, to provide such means which may be adjustable and for the purpose hereinafter explained.

This object is attained by, and the invention finds preferable embodiment in, the structure and mechanism hereinafter particularly described in the body of this specification and illustrated by the accompanying drawings, in which:—

15 Figure 1 is a side view of an automobile's internal-combustion engine to which my cooling means is applied, the casing of the engine being partially broken away;

20 Figure 2 is a top plan view of the same, the cap member of the casing being removed; and

25 Figure 3 is a detail view (enlarged) of a portion of the means for moving the air-deflectors to a desired adjusted position.

30 In the embodiment of the invention illustrated by the said drawings, an automobile's internal-combustion engine, designated generally 1, is shown comprising six cylinders 2 disposed in the longitudinal direction of the automobile. A casing, designated generally 3, encloses this engine and comprises a lower member 4 and an upper or cap member 5 removably engaging the said lower member. This casing is spaced laterally

35 from the engine (i. e., from its top and from its right-hand and left-hand sides) so as to provide an air passage extending between the engine and the casing from an inlet 6 at the engine's forward end 7 to an outlet 8 at the rear end 9 of the engine. The forward movement of the traveling automobile drives the air rearwardly through this passage; or, particularly when the automobile is not traveling, air is forced through said

40 passage by the usual fan 10 rotated by the engine shaft 22 and the belt 11. A plurality of air-deflectors are mounted in said passage extending in series in the longitudinal direction of the engine and automobile, such deflectors 12 being carried by the cap portion 5 above the cylinders, and the air-deflectors 12¹ being carried by the casing's lower member 4 at the engine's right-hand side, and the deflectors 12² being carried by

45 said lower portion of the casing at the left-hand side of the engine. The deflectors 50

comprising each of these three series increase in length successively toward the outlet end 8 of the air passage, and are swingably mounted at 13 on the casing. 60

Means are provided for swinging these air-deflectors toward and away from the engine so as to contract or expand said passage, such means serving to hold the air-deflectors in the position to which they are 65 thus swung. In the construction shown, such means comprises a link 14 pivotally connected at 15 to a plurality of the air-deflectors comprising such system, the link being movable to swing the air-deflectors by 70 suitable means, such as the screw 16 threaded in the casing and having a contracted shank portion 17 extending through a longitudinal slot 18 in the link, the head 19 of the screw serving to retain the shank portion in said slot. This screw may be manually turned by its knob portion 20 extending outside the casing, so as to move the link and the air-deflectors with it toward 75 and away from the engine for the purpose 80 set forth. An air-deflector 21 between the fan 10 and the front end of the engine, concentric with the axis of the fan's rotation and cross-sectionally enlarging rearwardly, 85 may be provided to drive the air toward the casing and the air-deflectors mounted thereon.

The invention being intended to be pointed out in the claims, is not to be limited to or by details of construction of the particular embodiment thereof illustrated by the drawings or hereinbefore described. 90

I claim:

1. In an organization of the character described: an internal-combustion engine comprising a plurality of cylinders disposed in the longitudinal direction of said organization; a casing spaced laterally from the engine to provide an air-passage therebetween; a plurality of movable air-deflectors disposed in said direction in said passage and increasing in length successively toward its discharge end; means for moving the deflectors together and for holding the same in adjusted positions relatively to the engine to contract or expand said passage. 95

2. In an organization of the character described: an internal-combustion engine comprising a plurality of cylinders disposed in the longitudinal direction of said organization; a casing spaced laterally from the engine to provide an air-passage therebe- 100 105 110

tween; a plurality of swingably-mounted deflectors disposed in said direction in said passage; a link connecting the deflectors to swing the same together toward and away from the engine to contract or expand said passage; a threaded element engaging the link and turnable to move the same and the

deflectors therewith to adjusted positions relatively to the engine.

In testimony whereof I have hereunto set my hand at Grand Rapids, Michigan, this 15th day of March, 1927.

CHARLES X FORBES.
